UNITED STATES PATENT OFFICE.

ALBERT E. WELSH, OF LEWISTON, IDAHO.

CALENDAR.

Application filed September 29, 1927. Serial No. 222,817.

This invention relates to card, picture and sign exhibitors and more particularly to a calendar intended to be used in banks, real estate offices and other commercial houses.

- 5 One object of the invention is to provide a calendar of the perpetual type which may be used from one year to another and is provided with means for indicating the month, the day thereof and the week day.
- 10 Another object of the invention is to provide the calendar with a date pad consisting of a plurality of leaves assembled in book form and each having one face marked to indicate the date and its other page provided with an advertising legend or the like so that when the book is open and the pages successively moved to disclose the proper date there will always be disclosed two pages, one having the date marked thereon and the other 20 disclosing advertising matter.

Another object of the invention is to provide improved means for retaining the book of date sheets open at the proper place.

- Another object of the invention is to provide an improved type of frame for the calendar including channels in which strips having month and day markings thereon are movably mounted and disclosed through openings formed in a facing sheet mounted upon the 30 frame and carrying the date pad.

Another object of the invention is to permit the month and day strips to be wound upon rollers disposed transversely in the channels of the frame and cause them to be 35 unwound by the action of weights carried by the strips when the rollers are rotated in the proper direction.

- Another object of the invention is to yieldably prevent the rollers from being rotated in 40 an unwinding direction.

The invention is illustrated in the accompanying drawing, wherein

Figure 1 is a view showing the improved calendar in front elevation;

- 45 Fig. 2 is a rear elevation of the calendar;

Fig. 3 is a longitudinal section view through the calendar taken on the line 3—3 of Fig. 1;

- 50 Fig. 4 is a view of a date pad or book of the type intended for use in a real estate office, and

Fig. 5 is a fragmentary perspective view showing one of the spring pawls constituting part of the invention.

The frame forming part of the calendar is preferably formed of wood and includes inner and outer longitudinally extending strips 1 and 2 having their upper ends suitably secured to transversely extending end strips 3 and 4. Corner braces 5 are provided to strengthen the frame and hold it in proper shape. There has also been provided a cross bar 6 which extends between the inner side strips to brace the frame intermediate its depth. This frame carries a facing sheet 7 which is preferably formed of cardboard, although sheet metal, leather or any other suitable composition may be employed.

The date pad which is indicated in general by the numeral 8 consists of a suitable number of leaves held together in book form by paper fasteners or the like 9 which are passed through the leaves at the center of the book and through the facing sheet with their end portions clinched against the rear face of the facing sheet, as shown in Figs. 1 and 2. By 70 referring to Fig. 1, it will be seen that each sheet has a numeral 10 printed thereon to indicate the day of a month and may also have an advertising slogan 11 printed thereon. Upon the other face of each sheet may be 75 printed an advertising slogan, as shown at 12, or if the calendar is for use by a real estate firm or the like, a picture 13 of a house may be secured to the second-mentioned face of each sheet of the date book by stickers 14. 80 These stickers 14 are disposed at the corners of the picture and are formed with tongues 15 which overlap the outer face of the picture and with a diagonally extending strip 16 beneath which the extreme corner portions 90 of the picture are passed. The under faces of the stickers are gummed so that they will firmly adhere to the leaves of the date book. If desired, the pages of the book may contain 95 illustrations of a manufacturing plant and appropriate descriptive matter or advertising slogans intended to induce purchases from the company distributing the calendars. Clips 17 are carried by the facing sheet 7 above and below the date book to engage the 100 leaves in order to retain the book open with a desired date exposed to view and prevent the pages from becoming curled or torn by wind. Each of the clips is formed from a strand of resilient wire bent to provide a cross bar 105 having a lifting lip 18 intermediate its length.

and side arms 19 having eyes at their ends through which are passed securing bolts 20. The bolts 20 pass through the facing sheet and through end portions of metal strips 21 which serve to reinforce the facing sheet and prevent danger of the bolts being worked through the facing sheet if formed of paper or the like. A sheet 22 having the name of the bank or other business house using the calendar is pasted or otherwise secured against the upper portion of the outer face of the facing sheet.

The month and day of the week are indicated by strips 23 which are disposed in channels defined by the inner and outer strips 1 and 2 of the frame and have the names of the months printed upon them, as shown at 24 and 25 in Fig. 1, which are viewed through sight openings 26 and 27 formed in the facing sheet and communicating with the channels. These strips 23 are wound upon rollers 28 and each roller is provided with a pin or axle 29 journaled in the strips 1 and 2 and having one end portion projecting outwardly and carrying a turning head 30. The peripheral edge face of the turning head is serrated so that it may be easily grasped in order to rotate the roller and also in order to provide ratchet teeth engaged by a pawl 31 which serves to yieldably resist turning of the head. By referring to Fig. 5, it will be seen that each pawl consists of a strand of resilient wire folded back upon itself and having its ends twisted together and bent about a securing screw 31'. A guide strip 32 which may be formed of cardboard or sheet metal extends across each channel opposite the sight opening communicating therewith and is provided with end flanges 33 secured against the side strips 1 and 2. By an inspection of Figs. 2 and 3, it will be seen that the strip 23 is passed between the guide strip 32 and facing sheet and, therefore, will be held close to the opening so that the name of the month or day may be easily read through the opening. It should also be noted that each strip 23 carries a weight 34 at its lower free end so that when the roller is rotated in an unwinding direction the weight will move the strip downwardly through the channel until the strip is unwound and the weight rests upon the bottom of the channel. The weight will also serve to hold the strip taut and prevent it from winding unevenly upon the roller. A guide strip 35 which is curved transversely, as shown in Fig. 3, extends between the strips 1 and 2 in shielding relation to the roller and prevents the cover sheet or backing sheet 36 carried by the strips 1 and 2 from bearing against the roller and preventing it from rotating easily.

When the calendar is in use, a sheet 22 bearing the name of the bank, real estate office or other business house is applied to the upper portion of the outer face of the facing sheet

and the calendar may be suspended from a nail or other suitable support by means of the hanger 37 or may be supported in an upright position in any other desired manner. The strips 23 are adjusted to display the name of the month and day of the week through the openings 26 and 27 and the book of date leaves is opened to display the sheet bearing the numeral indicating the proper day of the month. Each day one of the date leaves is released from the lower clip 17 and moved upwardly into engagement with the upper clip and the roller carrying the strip having the names of the days printed thereon is rotated to move the strip upwardly and display the proper day through the opening 26. Of course, at the first of each month the roller carrying the strip having the names of the months printed thereon must be rotated to draw its strip upwardly and display the proper month through the opening 27. It will thus be seen that the calendar is of the everlasting type and may be used from one year to another. At any time desired the book of date sheets may be removed by releasing the paper fasteners and a new one substituted. In order to unwind the strips 23, it is merely necessary to flex the pawls 31 out of engagement with the ratchet wheels 30 and the weights will move downwardly until they rest upon the bottoms of the channels. This will, of course, cause the strips to be unwound from their rollers.

Having thus described the invention, I claim:

1. A calendar comprising a frame including strips defining a vertically extending channel having side walls and upper and lower end walls, a facing sheet carried by said frame and having an opening communicating with said channel, a roller extending transversely in said channel and having a stem journaled in the side walls and projecting from one side of the frame, a turning head carried by said stem, a pawl carried by said frame and engaging said head to yieldably resist turning of said roller, a ribbon wound upon said roller and having characters thereon displayed through the opening in said facing, a weight for the free end of said ribbon, and a guide for said ribbon extending behind the same in the channel in crossed relation to said opening.

2. A calendar comprising a frame having vertically extending strips and cross strips connecting the vertical strips and together with the same forming vertically extending channels, a facing for said frame having openings communicating with said channels, rollers extending transversely in said channels above said openings, stems for said rollers projecting from the sides of said frame, a turning head carried by the projected portion of each stem, ribbons wound upon said rollers and movable longitudinally

in the channels across the openings and having characters disclosed through the opening, guide strips extending across said ribbons opposite the openings to retain the ribbons close to said sheet, a weight carried by the free end of each ribbon, means engaging said turning heads to yieldably resist rota-

tion of the rollers in a direction to unwind the ribbons, shields for said rollers carried by the vertical strips of said frame, within the channels, and a backing sheet carried by said frame. 10

In testimony whereof I affix my signature.
ALBERT E. WELSH. [L. S.]
